UNITED STATES PATENT OFFICE

109,917

DESIGN FOR AN EGG TESTER

Hermann Lukowski, New York, N. Y.

Application December 21, 1937, Serial No. 73,789

Term of patent 7 years

To all whom it may concern:

Be it known that I, Hermann Lukowski, a citizen of Germany, residing at 225 Lafayette Street, New York city, in the county of New York and State of New York, have invented a new, original, and ornamental Design for an Egg Tester, of which the following is a specification, reference being had to the accompanying drawing, forming part thereof.

In the drawing:

I claim:

The ornamental design for an egg tester, as shown.

HERMANN LUKOWSKI.
